UNITED STATES PATENT OFFICE.

WILLIAM W. EVANS, OF SALT LAKE CITY, UTAH.

FLUE-CLEANER.

1,359,239.

Specification of Letters Patent. Patented Nov. 16, 1920.

Application filed March 6, 1920. Serial No. 363,717.

To all whom it may concern:

Be it known that I, WILLIAM W. EVANS, a citizen of the United States, residing at Salt Lake City, in the county of Salt Lake and State of Utah, have invented new and useful Improvements in Flue-Cleaners, of which the following is a specification.

My present invention pertains to tools for cleaning flues of boilers and the like, and it 10 contemplates the provision of a device that is simple in construction and easy to operate and one whereby soot or other foreign matter may be thoroughly removed from the flues of a boiler and the like.

15 The invention further contemplates the provision of a flue cleaner in which the possibility of the same becoming jammed in the flue, during the cleaning operation, is greatly diminished.

20 Other objects and advantageous characteristics of the invention will be fully understood from the following description and claims when the same are read in connection with the drawings accompanying and forming part of the specification in which:—

25 Figure 1 is a longitudinal section illustrating my novel flue cleaning device and relative arrangement of parts with respect to each other.

30 Fig. 2 is a detail view of one of the breakers or blades comprised in my novel device.

35 Fig. 3, is a view illustrating the arrangement of cutting disks on the bolt of the device.

Fig. 4 is a detail view of one of my novel sweeping devices.

40 Fig. 5, is a front elevation of the four post washer, I employ between the sweeping rings whereby said rings are held in vertical position while carrying the load of dust present in the boiler flue.

45 Similar numerals of reference designate corresponding parts in all of the views of the drawings.

50 My novel device comprises the breaker plates 4 and the cleaning or cutting disks 5 and interposed between each pair of cutting disks are sweeping rings or disks 6 as clearly shown in Fig. 1.

55 By reference to the drawings it will be seen that the active parts of my device are held in place by the spacers 3 and interposed between the two sweeping rings is the washer 7 that is provided with the posts or portions 7^a, Fig. 5.

It would be well to state at this point, that in cleaning flues, it is sometimes advantageous to remove all of the parts from the handle except the breakers 4 and the 60 spacing rings and after the device has been used in this manner, the completed device including the sweeping rings and cleaning disks is intended to be run through the flues. Of course, this is optional with the 65 operator of the device.

By reference to Fig. 3, it will be seen that the cleaning disks are provided with a flange 5^c at the end of the blade and this flange has the same curvature as the inner 70 surface of the flue, the said disks are flexible and preferably formed of sheet metal and in forcing the device through the flues the ends of the cleaning disks come in contact with the inner surface of the flue and as they naturally spring back into place the flange is turned out so as to engage the inner 75 surface of the flue.

By reference to Fig. 3 it will be noted that the various elements of the device are 80 placed in staggered relation with respect to each other on the bolt 1^a and this is done so that the blades operate in a manner similar to the teeth of a saw.

It will be noted by reference to Fig. 1 85 that the device is applied in a flue A, and the various elements of the device are arranged on a bolt or body portion "1^a" having a head 1 and in rear of said head, I provide a collar or guard ring 2. The body 90 1^a is threaded to the collar 8, and said body 1^a is secured to the guard or collar 9, by means of the interior threads of said collar engaging the threads of the said body. The guard 9 is provided with an integral portion 9^a that is interiorly threaded and receives the handle 10 of my novel device.

It will be noticed from the drawings that the breaker-plates are made somewhat smaller than the diameter of the flue and in 100 operation they remove a portion of the baked crust, thus making it an easy matter for the cleaning disks and sweeping rings to perform the further process of cleaning. The disks 6 of my novel device face in opposite directions whereas each of the cleaning disks 5 are provided with a flange 5^c on each side thereof, and hence it will be manifest that notwithstanding the directions of movement of the device as a whole within 105 a flue, the sweeping rings and cutting disks will function. It will be noted further, that

the sweeping rings are provided with a circumferential flange on their outer side, said flange being numbered 6^a. The disks 6 are provided in their centers with the opening 5 6^b and said opening is slightly larger than the circumference of the bolt 1^a and hence when the device is forced into a flue said disks will not bear at their centers on the bolt but will ride on the walls of the flue.

10 I would have it understood that should any part become worn it is simply necessary to place a wrench on the head of the bolt and remove the device from the handle and then remove the portion 8 from the bolt 15 when any portion of the device may be displaced from the bolt; the bolt being provided with a key-way on which the key of the breakers and cleaning disks slides.

The washer 7 is designed to hold the 20 sweeping rings vertical and to keep them from falling over while carrying the load.

It will be apparent that I employ but one washer 7 for the reason that if more than one washer were employed between the 25 sweeping rings they would prevent proper operation of the cutting disks. The sweeping rings are loose and ride freely on the bottom of the flue.

The cleaning disks as shown at 30 5^b are provided with corrugations that prevent said disk from buckling and thus sticking in the flue.

It will be appreciated from the foregoing 35 that my novel device will effectually remove all incrustations from a boiler flue or the like and will not only remove the same but will also sweep it from the boiler which is materially advantageous when it is borne in mind that such foreign matter prevents the 40 proper working of the boiler. Moreover, the fact that the worn parts may be removed and replaced with new parts prolongs the life of the tool for an indefinite period of time and experience has demonstrated that 45 the only parts subject to excessive wear are the cleaning disks 5.

The rings and disks may be arranged on the bolt as illustrated or with the sweeping disks immediately behind the breaker plates.

Having described my invention, what I claim and desire to secure by Letters-Patent is:

1. In a device for the purpose set forth, 55 the combination of a headed bolt having a channel formed in the shank thereof, a collar on said bolt adjacent the head, a breaker-plate having an aperture in its center with a projection formed therein; said plate being arranged on the bolt in rear of the collar and having sharp beveled edges on its outer surface, a series of cleaning plates arranged on the bolt in rear of the breaker-plate, said plates having flanges formed on their outer 60 ends and faced in two directions, sweeping 65

disks arranged on the bolt in rear of the cleaning disks and having a cutting flange on their outer circumference; one of said disks being arranged so that its flange points in one direction and the other of the disks 70 being arranged so that its flange points in a direction opposite that of the first-named disk, a washer interposed between the disks, a second series of cleaning plates similar to the first named plates arranged in rear 75 sweeping disks, a breaker plate similar to the first plate arranged on the bolt in rear of the second series of cleaning plates, a guard having a portion provided with interior threads that secure the guard on the 80 bolt, and a handle threaded in the portion of the guard.

2. In a device for the purpose set forth, the combination of a headed bolt having a threaded end and a longitudinal channel, a 85 collar on said bolt bearing against said bolt, a guard on the threaded end of the bolt, breaker-plates, having portions that extend into the channel of the bolt; said breaker-plates being positioned on said bolt between 90 the collar and guard, a series of plates interposed between the breaker-plates, and a pair of disks interposed between the series of plates; said plates and disks being provided at their outer ends with flanges for 95 cutting and sweeping incrustations from boiler flues.

3. In a device for removing incrustations from a boiler, the combination of a headed bolt having a longitudinal channel in its 100 shank, a guard secured on said bolt, a handle secured to said guard, breaker plates having cutting edges on their outer surfaces and also having an opening in their center; a projection in the center of each plate that 105 enters the channel of the bolt when the plates are arranged thereon, sweeping disks interposed between the plates on the bolt and having an opening in their center of slightly larger circumference than the circumference of the bolt and being provided with oppositely directed cutting flanges on their outer ends, a washer interposed between said disks and having outwardly-reaching posts, and a series of cleaning plates 110 arranged on the bolt and interposed between each disk and breaker-plates; said cleaning plates having cutting flanges arranged on their outer end and faced in both directions with respect to the length of the bolt; all 115 of the breakers, disks and plates being arranged in staggered relation on the bolt with respect to each other.

In testimony whereof I have hereunto set my hand in presence of two subscribing witnesses.

WILLIAM H. EVANS.
